UNITED STATES PATENT OFFICE

JOHN C. STOKES, OF HOUSTON, TEXAS

MEANS FOR SUPPORTING SUCKER ROD AND PUMP LINES

Application filed June 21, 1928 Serial No. 287,076.

This invention relates to improvements in means for supporting sucker rods in well tubing or pipe lines.

The primary object of this invention is 5 the provision of means for supporting the dead weight of a long string of sucker or pumping rods, in deep well pumping equipment, in order to distribute the load thereof at spaced intervals along the tubing or casing, for the purpose of relieving the operating mechanism and preventing destruction to parts.

A further object of this invention is the provision of improved means for resiliently 15 supporting sucker rods within well tubing and the like, the invention being generically set forth in my co-pending application, Serial No. 231,907, filed November 8, 1927, and differing thereover in the novel means of 20 supporting springs both with respect to the sucker rod line and the tubing.

Other objects and advantages of the invention will be apparent during the course of the following detailed description.

25 In the accompanying drawings, forming a part of this specification, and wherein similar reference characters designate corresponding parts throughout the several views,

30 Figure 1 is a vertical fragmentary sectional view of pump tubing, showing the preferred type of reciprocating sucker rod pump line and its supporting means.

Figure 2 is a transverse sectional view 35 taken substantially on the line 2-2 of Figure 1.

Figure 3 is a view similar to Figure 1, of a modified form of the invention, showing an improved detent means for supporting 40 the spring devices of sucker rod lines within the well tubing.

Figures 4 and 5 are cross sectional views taken substantially on their respective lines in Figure 3 of the drawings.

45 Figure 6 is a fragmentary sectional view taken through the pawl receiving coupling of the tubing of the form of invention shown in Figure 3, showing the relation of the pawl carrying member therein.

50 In the drawings, wherein for the purpose

of illustration are shown preferred and modified forms of the invention, the letters C and D may respectively designate the preferred and modified forms of the invention.

In the form of invention C a tubing line K is provided, consisting of conventional lengths of tubing 10, connected at desired locations by special couplings 11 which provide upwardly facing beveled shoulders 12 projecting in upwardly facing relation in the passageways 13 through the tubing sections 10.

It is the generic purpose in providing the forms of invention C and D to permit withdrawal of the sucker rod lines, together with the spring devices attached thereto, which are adapted to support the sucker rod lines at various spaces along the tubing.

The sucker rod line L of the form of invention C includes the conventional sucker rod sections 15, the lowermost of which has the plunger or piston mechanism 16 connected therewith, operating in a conventional working barrel 17. At spaced elevations along the sucker rod line it is desired to distribute a portion of the load of the same upon the tubing K. To this end at such locations on the sucker rod line L it is preferred to provide a special insert length 20, for the respective sucker rod section, which at the upper end thereof clamps an annularly projecting washer 21, of ring-shaped formation, in a rigid location on the sucker rod line. At its lower end the special section 20 also clamps an annular ring-shaped washer 22 on the sucker rod line. These washers or members 21 and 22 form counter facing abutments or shoulders, as is clearly shown in Figure 1 of the drawing.

The spring arrangements M are provided on the sucker rod line L wherever the special rod sections are provided. They may be of one piece or comprise upper and lower spiral springs 25 and 26 respectively, seated at their proximate ends against spaced lugs 27 arranged in radial relation upon a spring guide sleeve 28. The springs are slipped over the opposite sleeve ends of the

100

guide member 28. The upper end of the spring 25 seats against the lower surface of the ring-shaped abutment 21, and the lower end of the spring 26 rests upon the top surface 29 of a slidable follower or sleeve 30, which is normally urged by the springs 25 and 26 against the lower washer 22.

When the sucker rod line is lowered, into a pumping position, it is apparent that the load of it will be distributed upon the tubing K at various elevations therealong, since the followers 30 will rest on the shoulders 12 of the tube couplings 11. The devices M will of course be held in position between the washers 21 and 22, as is apparent. It is to be particularly observed that in this form of invention, each of the followers 30 are of a decreasing width in external diameter from the uppermost spring arrangement M to the lowermost spring arrangement M, so that the follower 30 of the lowermost spring arrangement M, illustrated in the right hand portion of Figure 1, may readily pass upwardly through the passageways of the special couplings 11 for all of the spring arrangements M thereabove. This of course requires that the passageways of the special couplings 11 have a decreasing diameter from the uppermost coupling 11 of the tubing to the lowermost coupling 11. This structure permits a ready withdrawal of the entire sucker rod line, together with the spring arrangements M thereon, and insures that the followers or members 30 will seat only on the proper shoulders or abutments 12 of the tubing, as required.

In order to permit ready passage of the medium being pumped, the ring 21, instead of being annular may have spaced lugs 32, as shown more particularly in the upper right hand portion of Figure 1, and similarly the followers 30 may have a cross sectional appearance such as illustrated in Figure 2, that is, grooved longitudinally inwardly of the periphery at 33.

In the modified form of invention D, many of the structural features of the form of invention C are present, and like numerals indicate corresponding parts in both forms of the invention.

The tubing K' of the form of invention D is the same as the tubing for the form of invention C, except that the tubing couplings 40 are provided with annular recesses 41 facing in the tubing passageway. The height of these recesses 41 vary from the couplings 40 at the upper part of the tubing to the couplings 40 at the lower end thereof, in order to permit a ready passage of the sucker rod line, as will be more fully hereinafter disclosed.

In the form of invention D, the sucker rod line L' is the same as the sucker rod line L in the form of invention C, except that in

the form D the spring arrangements M' have the lower followers or members 50 thereof recessed to receive diametrically opposed pawls or dogs 51, pivoted at 52, at their upper ends; the lower portions thereof having springs 53 acting thereagainst, within the outer confines of the supporting followers 50, to force the lower tooth ends 55 of said pawls against the inside surfaces of the tubing, so that the said teeth will seat in the proper recesses 41 of the tube couplings 40, during the lowering operation of the sucker rod line.

To insure that the proper pawls or dogs 51 will seat at the proper elevation in the tubing, that is, in the respective coupling recess 41 provided therefor, as the sucker rod is being lowered, I vary the length of the pawl teeth 55, so that for the lowermost spring arrangement M', the said teeth 55 are longer than any of the other teeth of said pawls supported on the upper spring arrangements M'; the teeth 55 successively increasing in height from the uppermost spring arrangement M' towards the lowermost spring set M', as is shown in Figure 3 of the drawings. Of course, the recesses 41 in height are correspondingly designed for receiving only the respective teeth 55 of the pawls intended therefor. The teeth 55 are properly beveled on their upper shoulders to retract into the tubing upon an upward pull on the sucker rod line for releasing the same and withdrawing it from the tubing.

The general reference herein to a pumping line or pumping string is to be construed as including any reciprocatory pumping mechanism, such as rods, cable and the like where suitable, for supporting the dead weight thereof in the manner described.

Various changes in the shape, size, and arrangement of parts may be made to the forms of invention herein shown and described, without departing from the spirit of the invention or the scope of the claims.

I claim:

1. In well pumping equipment a string of tubing, a sucker rod line operable in the tubing, a spring device in the tubing, means to yieldably support the sucker rod line on the spring device, and means comprising a spring urged pawl on the spring device detachably engageable with the tubing to transmit the weight of the sucker rod line to the tubing through the spring device.

2. In pumping equipment a line of tubing, a sucker rod string reciprocable in the tubing, a spring arrangement upon the sucker rod line, means on the spring arrangement and tubing for yieldably distributing the weight of the sucker rod line onto the tubing, the spring arrangement and last mentioned means being so related that the sucker rod string and spring arrangement may be completely detached from the

tubing without interference on the part of the latter.

3. In deep well pumping equipment a line of tubing, a sucker rod string reciprocable in the tubing line, and spring devices supported by the sucker rod line and detachable from the tubing with the sucker rod line without interference by the tubing, said tubing and spring devices having interen-
10 gaging means thereon to respectively dis-
tribute the load of the sucker rod line at various elevations along the tubing.

4. In well pumping equipment a string of tubing having a plurality of seats at spaced 15 distances therealong with passageways through said seats varying in diameter from the uppermost seat to the lowermost seat, the passageways successively increasing in diameter from the uppermost seat to the 20 lowermost seat, a sucker rod line, and means on the sucker rod line at spaced intervals therealong for the respective seats, adapted to engage their respective seats at the same time for supporting the sucker rod line at 25 a plurality of spaced locations along the tubing.

5. In well pumping equipment a string of tubing having upwardly facing seats at spaced intervals therealong, the seats having 30 passageways therethrough of varying diameter, with the uppermost seat having its passageway largest and with the passageways of the succeeding lower seats being successively restricted, a sucker rod line, 35 and supports carried by the sucker rod line at spaced intervals therealong adapted to each engage a respective seat of the tubing, the supports for the lower seats being of a cross dimension that will permit them to 40 slip by the uppermost seats and engage only on their respective seats.

6. In well pumping equipment a string of tubing having upwardly facing seats at spaced intervals therealong, the seats having 45 passageways therethrough of varying diameter, with the uppermost seat having its passageway largest and with the passageways of the succeeding lower seats being successively restricted, a sucker rod line, 50 supports carried by the sucker rod line at spaced intervals therealong adapted to each engage a respective seat of the tubing, the supports for the lower seats being of a cross dimension that will permit them to slip by 55 the uppermost seats and engage only on their respective seats, said supports having means resiliently connecting them on the sucker rod line for limited sliding movement therealong.

60 7. In well pumping equipment, tubing having an upwardly facing shoulder therein, a sucker rod line having spaced facing shoulders thereon, a follower sliding on the sucker rod line between said shoulders, and 65 a spring device engaging the upper shoulder

and urging the follower towards the lower shoulder of the sucker rod line, the follower being in position to engage the shoulder of the tubing when lowered into the tubing.

8. In well pumping equipment, tubing having an upwardly facing shoulder therein, a sucker rod line having spaced facing shoulders thereon, a follower sliding on the sucker rod line between said shoulders, a 70 spring device engaging the upper shoulder and urging the follower towards the lower shoulder of the sucker rod line, the follower being in position to engage the shoulder of the tubing when lowered into the tubing, 75 said tubing and sucker rod line having similar structures to that above mentioned at spaced intervals therealong for supporting the sucker rod line in the tubing at a plurality of spaced locations therealong.

9. In well pumping equipment, tubing having a recess therealong, a sucker rod line reciprocable in the tubing, spaced facing shoulders on the sucker rod line, a follower on the sucker rod line slidable between said shoulders, a spring arrangement engaging the upper shoulder of the sucker rod line and engaging the follower to force the latter against the lowermost shoulder of the sucker rod line, and a spring urged pawl carried by the follower normally urged at an end therefrom against the tubing to seat in the recess of the tubing when the sucker rod line is lowered to such extent.
